PACKAGE AND WRAPPER FOR FORMING SAME

Lewell O. McCullough, Charlotte, Clegg E. Price, Matthews, and Charles H. Beam and Ralph F. Skinner, Charlotte, N. C., assignors to Lance, Inc., Charlotte, N. C., a corporation of North Carolina

Application November 26, 1952, Serial No. 322,672

2 Claims. (Cl. 229—16)

This invention relates to wrappers and more especially to a wrapper for and process of packaging relatively small articles or groups of articles such as crackers, cookies, sandwiches and the like.

As is well known, various articles such as crackers, sandwiches, cookies and the like are wrapped in a sheet of web material made from regenerated cellulose or some plastic material such as cellophane, "glassine" or the like. The ends of such wrappers are usually folded in overlapping relation to each other at opposite sides of the package or articles contained therein and it is extremely difficult to remove the wrapper from its contents because the smooth, unbroken overlapping edges of said web material offer resistance to tearing.

It is therefore an object of this invention to provide an improved process of wrapping an article, wherein an improved wrapper is utilized. The wrapper is formed from a substantially rectangular blank having a tearing-strip, preferably a band of the same material as that of the blank, extending transversely thereof and adhesively or cohesively affixed thereto. The blank is provided with slits, nicks or notches at opposite longitudinal edges thereof, there being a pair of slits disposed astride each end of the tearing-strip and, in addition, the blank is formed with a third slit in each of its longitudinal side edges which is so positioned that, when opposite portions of the wrapper or blank are folded in overlapping relation to form seams at opposite sides of the articles, and sealed by the application of heat thereto, an outer seam edge with a pair of slits therein and an inner seam edge with one slit therein is formed on each of opposite sides of the package. One of said slits of said pair in each outer seam edge is disposed in substantial alinement with the corresponding third slit formed in the inner seam edge.

Thus, the wrapper may subsequently be removed by grasping one end of the tearing-strip and, since slits are formed in the corresponding edge of the wrapper, the seal is readily broken. As the tearing-strip is pulled away from the package, the wrapper tears easily until substantially the entire length of the tearing-strip has been torn away. Then, the notch or slit in the inner seam edge which coincides with the pair of slits or notches which straddle the opposite or still-attached end of the tearing-strip, breaks the seal of the package at that side of the package whereupon the upper portion of the package may be opened in substantially the manner of the cover of a box. Since the seal of the package will have been broken, the entire upper portion or cover defined by the portion of the wrapper that has been torn away may be readily removed from the body of the package.

Some of the objects of the invention having been stated, other objects will appear as the description proceeds, when taken in connection with the accompanying drawings in which—

Figures 1 to 4 are isometric views of the package in successive stages of the wrapper being folded about the articles contained therein;

2

Figure 5 is an isometric view of the package formed from the completely folded and sealed wrapper;

Figure 6 is an isometric view of the opposite side of the package from that shown in Figure 5 with a substantial portion of the tearing-strip pulled away from the package to illustrate how the seal of the wrapper is broken for subsequently removing the cover of the package defined by said tearing-strip.

In my co-pending application entitled Pull-Tape Applicator and Web Slitting Apparatus and Method, Serial No. 322,671, filed of even date herewith, there are shown means for forming slits in opposite edges of successive wrapper blanks severed from a web material after applying a tearing-strip or pull-tape to the web material. Referring to the drawing, the blank of the wrapper is generally designated at 10 and is formed from a heat-sealable material, such as regenerated cellulose or some plastic material, such as cellophane or the like. This blank 10 is adapted to be formed as a wrapper or package when wrapped around an article or group of articles generally designated at A.

The blank 10 is substantially rectangularly-shaped, thus being provided with opposite longitudinal side edges 11 and 12 and opposite transverse end edges 13 and 14. A tearing-strip or pull-tape 15 is adhesively or cohesively secured to one face of the blank 10 and extends from the first side edge 11 to the second side edge 12 of the blank and is also spaced inwardly from the end edge 14. The tearing-strip or pull-tape 15 is preferably made from the same material as the wrapper blank 10.

The side edges 11 and 12 of the blank 10 are formed with respective pairs of nicks or slits or notches 16, 17, and 20, 21 which are disposed astride opposite ends of the tearing-strip or pull-tape 15. The side edges 11 and 12 are also provided with respective third slits or notches 22 and 23 which extend toward each other and are spaced inwardly from the end edge 13 substantially the same distance as the slits 17 and 21 are spaced inwardly from the end edge 14 of the blank 10.

The blank 10 may be formed as a wrapper enfolded around an article or group of articles A by a wrapping machine such as that disclosed in the patent to John W. May, No. 2,526,824 of October 24, 1950.

In the formation of the package, the opposite end portions of the blank 10 defined by the edges 13 and 14 are folded upwardly against opposite sides of the article A to form end panels 25 and 26. The tape 15 is then held between the wrapper and the article. Thereafter, the exposed portions of the blank between said end panels 25 and 26 are folded upwardly against opposite sides of the article A to form lower side panels or tucks 30 and 31, after which the edges 11 and 12 of the end panel 26 are folded inwardly against opposite sides of the package to form gusset side panels or side flaps 32 and 33 in which position the slits 22 and 23 are preferably disposed above the upper edges of the lower side panels or tucks 30 and 31.

The edges 11 and 12 of the end panel 25 are then folded inwardly thereby forming outer gusset panels or side flaps 34 and 35 positioned over the proximal portions of the gusset panels 32 and 33 to form seams wherein the slits 17 and 21 in the outer seam edge coincide substantially with the respective slits 22 and 23 in the inner seam edge.

Opposite sides of the package are then sealed, such as by the application of heat thereto, to cause the overlapping inner and outer seam edges of the side gusset panels 33, 35 and 32, 34 to adhere to each other.

This completes the formation of the bottom, side and end wall portions of the package. Thereafter, the upper central portions of the panels 25 and 26 are folded inwardly atop the article A to form top panels or tucks

36 and 37, respectively, whose proximal edges are usually spaced slightly from each other. Gusset-like flaps 40 and 41, which are formed from the upper proximal portions of the overlapping side flaps 32, 34, and 33, 35, respectively, are then folded inwardly in partially overlapping relation upon the top panels or tucks 36 and 37, after which the seam formed by the overlapping portions of the flaps 40 and 41 is adhesively joined, as by being subjected to heat to activate the material from which the wrapper 10 is formed, to also cause the top panels or tucks 36 and 37 to adhere to the top flaps 40 and 41. This completes the formation of the package and, of course, suitable labels, not shown, may be applied to the top and the bottom of the package thus formed, if desired.

It is thus seen that, in order to open the package as shown in Figure 5, it is merely necessary for the person opening the package to insert a finger nail underneath the outer seam edge at either of the edges 11 or 12 of the package, between the corresponding pairs of slits 16, 17 or 20, 21. Assuming the person opening the package inserts his finger nail under the edge 12 of the wrapper between slits 20 and 21, since the edge of the wrapping material is already fractured at this point, it is merely necessary to pull the tearing-strip or pull-tape 15 and a portion 42 is readily torn from the wrapper 10 parallel to the tearing-strip 15 until the portion 42 has been torn away around to the opposite side of the package at the seam of the gusset panels as shown in Figure 6.

Since the portion of the edge 11 of the wrapper 10 at the gusset panel 33 forms the inner seam edge beneath the corresponding portion of the gusset panel 35 which forms the outer seam edge, and the proximal portions of the gusset panels 33 and 35 have been sealed in overlapping engagement with each other, only the lower edge of the portion 42 will tear away from the article or articles A at this point while the upper edge of portion 42 at the seam of gussets 33 and 35 will not tear away because of there being only a single slit 22 coinciding with the slit 17.

Thus, the opening in the wrapper formed by the portion 42 torn from the package by the tearing-strip 15, defines a cover at the top portion of the package, including the tucks 36 and 37 and the flaps 40 and 41, and it is merely necessary to raise said cover, pivoting the same upwardly at that portion thereof adjacent which the portion 42 has been removed and, since the gusset panel 32 has the slit 23 therein and the gusset panel 33 has the slit 22 therein, the cover formed by the panels 36 and 37 and the flaps 40 and 41 will readily be separated from the major or lower portion of the wrapper to permit the access to the contents thereof.

In the drawings and specification there has been set forth a preferred embodiment of the invention and, although specific terms are employed, they are used in a descriptive and generic sense only, and not for purposes of limitation, the scope of the invention being defined in the claims:

I claim:

1. A wrapper extending about at least one article in a continuous manner to define a package, said wrapper being so folded about said article as to define overlapping outer and inner flap portions on at least two surfaces of said package, means for facilitating the opening of the package comprising a pull-tape secured to the wrapper and extending from one edge of one outer flap portion across the wrapper to one edge of the other outer flap portion, at least one of said outer flap portions having a pair of notches communicating with its edge and disposed astride the pull-tape, the inner flap portion of the other of said overlapping portions having at least one notch communicating with its edge and disposed subjacent the adjacent end portion of the pull-tape, and said overlapping portions being secured together whereby the end of the tape adjacent the pair of notches may be pulled to open the package and said notches serving to permit easy tearing of portions of the wrapper in which the respective notches are formed.

2. A package for an article comprising a rectangular wrapper, a tearing-strip extending transversely of said wrapper and being spaced inwardly from one transverse edge thereof, said wrapper being provided with a pair of slits at each longitudinal edge thereof disposed astride opposite end portions of the tearing-strip, said wrapper also having a third slit formed in each of its longitudinal edges and each third slit being spaced from the other transverse edge of the wrapper, one of the slits of each pair of slits and each of said third slits being substantially equally spaced from their respective transverse edges, said wrapper being so enfolded about said article as to form overlapping portions on opposed sides of the package, said overlapping portions each including a portion of said wrapper having said pair of slits therein and a portion of said wrapper having said third slit therein, one of said slits of each pair being positioned above one of said third slits to thereby enable an operator to readily tear the tearing-strip and a corresponding portion of the wrapper from said package formed therefrom and to enable the operator to readily remove the corresponding end of the package from the major portion of the package.
